ELECTROPNEUMATIC SIGNAL DEVICE

Roy R. Stevens, Forest Hills, Pa., assignor to The Westinghouse Air Brake Company, Wilmerding, Pa., a corporation of Pennsylvania

Application January 6, 1937, Serial No. 119,198

3 Claims.

(Cl. 177—7)

This invention relates to sound-producing devices and more particularly to the type having a vibratory element adapted to be operated by gaseous fluid under pressure, and the principal object of the invention is to provide an improved sound producing device of this type.

In the accompanying drawing Fig. 1 is a diagrammatic, sectional view of a sound producing device embodying the invention; and Fig. 2 is a partial, sectional view taken on the line 2—2 in Fig. 1.

As shown in the drawing, the sound-producing device comprises two casing sections 1 and 2 secured together by screws 3 and cooperating to form a chamber 4 which is connected to a pipe 5 through which fluid under pressure from any suitable source is adapted to be constantly supplied to said chamber.

A frusto-conical shaped casing section 6 is secured to a flange 7 on the casing section 2 by screws 8, and interposed and clamped between the flange 7 and the periphery of the casing section 6 is a flexible, preferably metallic, vibratory diaphragm 9 and a clamping ring 10, the diaphragm 25 being interposed between the flange 7 and ring 10.

The diaphragm 9 is provided centrally with an aperture 11 extending through a preferably integrally formed, outwardly extending tube 12 the end portion 13 of which is flared. A cone shaped vibratory element 14 made of any suitable material such as relatively stiff paper, is disposed in the flared casing section 6 with the small end secured to the end portion 13 of the tube 12 in any suitable manner, as by rivets 15. The larger, open end of the cone shaped element 14 is secured, preferably by rivets 16, to a flexible ring 17 made of any suitable material such as a rubber composition. The outer portion of this ring 17 is clamped against a peripheral flange 18 formed on the casing section 6, by a clamping ring 19 secured to flange 18 by bolts 20. The space around the exterior of the cone element 14 and at the right hand side of the diaphragm 9 45 is open to the atmosphere through a plurality of apertures 47.

A convex screen 53 made of a closely woven wire mesh material is provided over the large open end of the cone element 14 for excluding dirt and other foreign matter from the interior of said element, said screen being clamped in position between the rubber ring 17 and the clamping ring 19.

A horse-shoe type electro-magnet is disposed in chamber 4 and is secured to and insulated from suitable brackets 21 which in turn are secured to the casing section 2. This electro-magnet comprises a U-shaped core 22, a magnet coil 23 mounted on one leg of said core and

a magnet coil 24 mounted on the other leg of said core.

A pin 25 made of any suitable electrical insulating material, such as fibre, is secured in the end of each leg of the magnet core 22 and slidably mounted on the pins 25 is an armature 26 which is provided with spaced slots 27 for receiving the pins 25.

The armature 26 is provided midway of the slots 27 on the side opposite the core 22 with an extension on the end of which is provided a valve 28. A valve seat 29 adapted to be engaged by the valve 28 is provided in the end wall 50 of the casing section 2, around a port 51 which leads to a chamber 52 provided at the left hand side of the diaphragm 9.

A spring 33 is provided for urging the valve 28 into engagement with its seat 29 in which position the armature is spaced from the ends of the armature core 22. This spring is disposed in the space between the magnet coils 23 and 24 and is interposed between one side of the armature 26 and an adjusting nut 30 mounted on and having screw threaded engagement with an adjusting screw 31. A pin 32 extends from one side of the nut 30 into a groove 33' provided in the casing section to prevent said nut from turning and said pin is adapted to slide in said groove to permit movement of the nut on the adjusting screw.

The adjusting screw 31 has a collar 34 engaging the inner surface of the end wall of casing section 1 and extending from said collar through a suitable bore in said end wall to the outside of the casing is a journal portion 35 having in its end a slot 36 through the medium of which the screw may be turned by a screw-driver for adjusting the position of the nut 30 on the screw and thereby adjusting the pressure of the spring 33 on the armature 26. The opposite end of the screw 31 is reduced in section and is slidably mounted in a suitable bore provided in the armature 26.

Two substantially rigid contact fingers 37 and 38 are secured to and suitably insulated from the casing section 2 within the chamber 4, one at either side of the valve 26 and with the end of the fingers arranged to engage the armature 26 when the valve 28 is seated.

The contact finger 37 is connected by a wire 39 to a terminal post 40 mounted in and insulated from the casing section 2. The contact finger 38 is connected by a wire 41 to one terminal of magnet coil 24 which is connected by wire 42 in series with magnet coil 23, which is in turn connected by a wire 43 to a terminal post 44 mounted in and suitably insulated from the casing section 2.

The terminal post 44 may be connected to any suitable source of electric current such as one

terminal of a battery 45. The other terminal of the battery may be connected to one contact of a switch device 46 the other contact of which is connected to the terminal post 40.

5 In operation, when the switch device 46 is closed the battery 45 is connected in series with the serially connected magnet coils 24, 23 by way of terminal post 40, wire 39, finger 37, armature 26, finger 38, wire 41, magnet coil 24, wire 42, 10 magnet coil 23, wire 43 and terminal post 44. The magnets 24 and 23 are thus energized and the armature 26 is pulled towards the ends of the core 22 against the opposing pressure of spring 33 and out of engagement with the contact fingers 37 and 38. This opens the circuit through the magnet coils 24 and 23 resulting in deenergization of the magnets which permits spring 33 to urge the armature 26 back into engagement with contact fingers 37 and 38 reestablishing 15 the electric circuit through the magnet coils 23 and 24. The magnet is thus again energized and the armature 26 is again pulled out of engagement with the contact fingers 37 and 38 following which the above operation is repeated. In 20 this manner the armature 26 is caused to vibrate and since the valve 28 is a part of and moves with said armature, said valve is alternately pulled away from its seat 29 by the magnet and urged to its seat by the spring 33, or in other words is 25 caused to vibrate with the armature 26 and permit an intermittent or rapidly recurring series of puffs of fluid under pressure to flow from chamber 4 into chamber 52.

When the valve 28 is opened, the puff of fluid 30 under pressure supplied to chamber 52 causes a slight increase in pressure therein which acts on the diaphragm 9 to cause it and the cone element 14 to move outwardly. When the valve 28 seats and cuts off the flow of fluid under pressure into 35 chamber 52, the pressure therein acting on the diaphragm 9 reduces through the aperture 11 in tube 12 and permits the diaphragm 9 and cone element 14 to move toward the left hand. Aided by the resilience of the diaphragm 9 and cone 40 element 14, said diaphragm and cone element are thus caused to vibrate at the same rate as the valve 28 is opened and closed and this causes the body of air in the cone element to be maintained in a state of vibration thereby producing 45 sound vibrations.

The pitch of the tone produced by the vibration 50 of the diaphragm 9 and cone element 14 depends upon the rate of vibration of the valve 28 relative to its seat 29 and may be varied by varying the 55 pressure of spring 33 on the armature 26. The pressure of the spring 33 is varied by turning the adjusting screw 31, through the medium of which the adjusting nut 30 may be moved either towards or away from the armature 26, as desired.

60 When it is desired to prevent further sounding of the signal device, the switch device 46 is opened thus cutting off the supply of electric current to the magnet devices. The spring 33 then acts to hold the valve 28 seated to prevent flow of 65 fluid under pressure from chamber 4 to chamber 52.

From the above description it will now be evident that a relatively simple and compact sound-producing device is provided by the use of a valve 70 and electro-magnetic means for effecting the operation of the valve to provide a recurring series of puffs of fluid under pressure to act on a vibratory element for effecting its operation to produce sound vibrations.

75 While one illustrative embodiment of the in-

vention has been described in detail, it is not my intention to limit its scope to that embodiment or otherwise than by the terms of the appended claims.

Having now described my invention, what I 5 claim as new and desire to secure by Letters Patent is:

1. A sound producing device comprising a vibratory diaphragm having at one side a chamber and adapted to be vibrated by successive increases 10 in fluid pressure in said chamber, a source of gaseous fluid under pressure, valve means controlling a communication through which fluid under pressure is adapted to be supplied from said source to said chamber, electromagnetic 15 means operative upon energization to effect movement of said valve means to a position for opening said communication and upon deenergization to effect movement of said valve means to another position for closing said communication, and means operative in one position of said valve means to effect energization of said electro-magnetic means and in the other position to effect deenergization of said electro-magnetic means, said diaphragm having an aperture 20 connecting said chamber to the atmosphere at the opposite side thereof, said aperture having a flow capacity so related to that of said communication as to cause a differential of fluid pressures to be established on said diaphragm when said 25 communication is open.

2. A sound producing device comprising a casting having a chamber supplied with gaseous fluid under pressure, a flexible diaphragm in said casting adapted to be vibrated by successive increases 30 in fluid pressure on one face, the opposite face of said diaphragm being subject to atmospheric pressure, valve means controlling a communication from said chamber to said one face of said diaphragm, an electro-magnet in said chamber, 40 means operative upon energization of said magnet to effect operation of said valve means to open said communication and upon deenergization of said magnet to effect operation of said valve means to close said communication, and 45 means operative automatically upon energization of said magnet to effect deenergization of said magnet and upon deenergization of said magnet to effect energization of said magnet, said device having means for releasing the fluid pressure 50 supplied to said one face of said diaphragm at a rate less than the rate of supply through said communication when open.

3. A gaseous operated sound producing device comprising a vibratory diaphragm having at one 55 side a chamber and having an aperture extending axially through the diaphragm, a conical vibratory element having its smaller end secured to said diaphragm around said aperture, flexible means carrying the larger open end of said conical element, a source of fluid pressure, a valve for opening a communication between said source and chamber having a flow capacity sufficiently in excess of said aperture to provide a differential of fluid pressures on said diaphragm for moving 60 said diaphragm and element in one direction, said diaphragm and element being movable in the opposite direction upon closure of said valve and equalization of the fluid pressures on said diaphragm, and means for vibrating said valve to open and close said communication and for thereby effecting variations in fluid pressure in 65 said chamber to effect vibration of said diaphragm and element.
